PULVERIZED COAL FEEDER

Filed Jan. 20, 1928

UNITED STATES PATENT OFFICE

FREDERICK F. FRICK, OF ANACONDA, MONTANA, ASSIGNOR TO ANACONDA COPPER
MINING COMPANY, OF ANACONDA, MONTANA

PULVERIZED-COAL FEEDER

Application filed January 20, 1928. Serial No. 248,227.

This invention relates to an apparatus for feeding pulverized coal or other comminuted fuel into an air line or furnace wherein the pressure is above atmospheric pressure.

5 Pulverized coal is usually fed into furnaces and boilers through calibrated screws from bins. The coal drops from the screw into a stream of air which sweeps it into the furnace. The pressure on the coal as it feeds 10 into the screw is atmospheric plus the weight of the coal. The pressure at the delivery end of the screw is atmospheric plus a few ounces of air pressure in most cases.

When it is desired to feed pulverized coal 15 into the tuyère pipes of a furnace like a copper converter or a blast furnace, so that the air blast will carry it into the furnace, a new problem is encountered. If an attempt is made to feed the coal against the air pressure 20 in the tuyère pipes, with an ordinary screw, the air pressure forces the coal back through the screw. This has been overcome in some cases by using a screw "choked" near the delivery end. This "choking" may be obtained 25 by decreasing the pitch of the screw near the delivery end or decreasing the clearance between the screw shaft and the housing near the delivery end. The object of either scheme is to compress the coal in the screw 30 near the delivery end so that it will resist the back pressure of the air on the delivery end of the screw. The "choked" screw has given reasonably good service in some cases particularly in the case of coals which are rather 35 greasy and which tend to lubricate the screw. It has been found, however, that this method of feeding coal is undependable. There is always a tendency, under varying conditions of physical character, fineness and wetness of 40 the coal, etc., for the "choked" screw to bind or clog. Another disadvantage of the "choked" screw is the small clearness necessary between the screw and the housing. This small clearness means more power and 45 more rapid wear of the screw and housing.

It has been found that an ordinary unchoked screw with reasonable clearance between screw and housing can be used with entire satisfaction if provision is made for 50 maintaining the gas pressure on the feed end

of the screw substantially equal to or greater than that at the delivery end. The arrangement preferably is such that the pressures are approximately the same on the feed and discharge ends of the screw. The invention will 55 be described in detail by reference to the accompanying drawing which illustrates one form of apparatus embodying the same.

Referring to the drawing:

Fig. 1 is a vertical section through the apparatus, and

Fig. 2 is a vertical elevation of a modification of that part of the apparatus shown in Fig. 1 which connects the delivery end of the screw with the tuyère pipes.

In the drawing, 1 is an air tight tank or hopper for pulverized coal which is divided by partition 2 into two intercommunicating compartments, the coal compartment 3 and an equalizing chamber 4. A coal charge pipe 5 closed by a cover 6 is provided at the top of the coal compartment. 7 is a pipe for supplying air under pressure to the tank 1. 8 is a screw which rotates in the housing 9 at the bottom of the coal compartment and delivers into the equalizing chamber. 10 is a conduit for receiving the coal falling from the delivery end of the screw and delivering it to the injector 11 which forces it through the pipe 12 into the tuyère pipes of the 80 furnace.

Fig. 2 shows a modification of the apparatus of Fig. 1 in which the injector 11 is omitted and a 90° curved pipe 13 is substituted therefor.

The operation of the device is as follows. Pulverized coal is passed into the coal compartment 3 through the charge pipe 5. The charge pipe is then sealed by means of the cover 6 or other suitable sealing means. The injector 11 is put into operation, air is supplied through the pipe 7 which is connected to the air line giving the main supply of air to the tuyères, and the screw 8 is started to revolve. The coal is fed at a rate depending upon the speed of revolution of the screw into the equalizing chamber from which it falls with the current of air flowing downwardly through chamber 4 into the conduit 90 10 and injector 11, whence it is carried into 100

the tuyères of the furnace which may be, for example, of the converter type in which the air passes into a molten bath or of the blast furnace type. As stated heretofore, 5 the pressure in the tank 1 should be approximately equal to or greater than the pressure in the air line or tuyères to which the coal is delivered, i. e., the pressures on the feed and discharge ends of the screw are approximately balanced.

10 This device has given perfect satisfaction. There is no clogging or binding of the screw and no clogging of the injector. The coal delivered from the injector is uniform in 15 quantity and is well distributed through the air.

15 It has been found that the use of the injector 11 is not necessary and that the device may be used with or without it. The injector simply assists and assures the delivery 20 of the coal into the tuyères. When the injector is not used the best results are obtained by maintaining the pressure in the tank somewhat higher than the pressure in the tuyères.

25 The primary object of the equalizing chamber is to equalize the pressure on both sides of the partition thus equalizing the pressure on both ends of the screw, and preventing "choking" of the screw. Another 30 function of this chamber is to allow pressure to be put on the tank so that the same or a slightly greater pressure can be maintained on the side of the injector receiving the coal feed than is on the side of the injector which 35 delivers the coal to the tuyères. In this way a satisfactory operation of the injector is obtained and a system with practically uniform pressure is thus maintained. It is obvious that the principle of my invention, i. e., the 40 approximate equalization of the pressures on the feed and discharge ends of the screw, may be accomplished in various other ways, and that therefore the invention is not limited to the precise apparatus herein described 45 except as is required by the terms of the appended claims.

50 The coal feeder described and illustrated herein is especially designed for use in connection with the apparatus disclosed in an application of Ulysses A. Garred, Serial No. 181,979, but it may be used on various types of furnaces and with any suitable pressures and quantities of air.

55 I claim:

55 1. An apparatus for feeding pulverized coal under pressure into the tuyère pipes of converter or blast furnaces comprising an air tight hopper divided into two intercommunicating compartments one of which is a coal compartment and the other an equalizing chamber, a pipe connected to the hopper for supplying air thereto under pressure, a screw for feeding the coal from the coal compartment into the equalizing chamber, a conduit

connected to the bottom of the equalizing chamber for receiving the coal and delivering it to the furnace.

2. An apparatus for feeding pulverized coal under pressure into the tuyère pipes of converter or blast furnaces comprising an air tight hopper divided into two intercommunicating compartments one of which is a coal compartment and the other an equalizing chamber, a pipe connected to the hopper for supplying air thereto under pressure, a screw for feeding the coal from the coal compartment into the equalizing chamber, a conduit connected to the bottom of the equalizing chamber for receiving the coal and an injector arranged to assist the delivery of the coal from the said conduit into the furnace.

In testimony whereof, I affix my signature.

FREDERICK F. FRICK.
